(57) **CLAIM**

The ornamental design for a trunnion support fitting for fluid pressure cylinder, as shown and described.

DESCRIPTION

FIG. 1 shows a front view of a trunnion support fitting for fluid pressure cylinder showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, front and left side perspective view thereof;

FIG. 8 shows a top, front and left side exploded perspective view thereof; and,

FIG. 9 shows a top, front and left side perspective view thereof in use with a fluid pressure cylinder.

The fluid pressure cylinder shown in broken lines in FIG. 9 is for the purpose of illustrating the environment only and forms no part of the claimed design.
